UNITED STATES PATENT OFFICE

2,603,431

COMBINED IRON REST AND IRONING CORD
RETRIEVERAllan H. Cramer, Inglewood, Calif., assignor of
one-half to Harry Lawrence Nielsen, Long
Beach, Calif.

Application May 6, 1947, Serial No. 746,179

1 Claim. (Cl. 242—107)

1

The present invention relates to new and useful improvements in equipment for use with electric irons and more particularly to a rest for the iron and having an ironing cord retriever constructed as a part thereof to automatically wind the cord as the iron is placed on the rest.

An important object of the present invention is to provide a combined iron rest and ironing cord retriever and embodying a unitary structure which may be easily and quickly secured in position on the top of an ironing board, work table, or other suitable supporting structure.

A further object of the invention is to provide a spring actuated drum for winding the ironing cord thereon and enclosed in a housing together with a collapsible support for the housing by means of which the same may be folded downwardly upon the iron rest into a substantially compact form for conveniently storing the device, when not in use.

A still further object is to provide a device of this character which is simple and practical in construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the combined iron rest and cord retriever mounted in position on an ironing board;

Figure 2 is a similar view showing the retriever folded downwardly upon the iron rest;

Figure 3 is an enlarged sectional view taken substantially on the line 3—3 of Figure 2 and with the iron rest removed from the ironing board;

Figure 4 is an enlarged fragmentary sectional view showing the housing for the cord retriever in a raised position;

Figure 5 is an enlarged vertical sectional view of the housing for the cord retriever;

Figure 6 is a sectional view taken on the line 6—6 of Figure 5; and,

Figure 7 is a similar view taken on the line 7—7 of Figure 6.

Referring now to the drawings in detail where-
in for the purpose of illustration we have disclosed a preferred embodiment of the invention, the numeral 5 designates the iron rest generally and which comprises a tray-like member 6 having its front edge open and provided at its front edge

2

with a beveled extension 7. The inner surface of the bottom of the tray is lined with a sheet of asbestos 8 or similar fire-proof and heat insulation material. A base member 9 projects rearwardly from the tray in the plane of the bottom thereof and is suitably secured to the tray.

The bottom of the tray 6 and the base member 9 are provided with openings 10 for receiving screws or other fastening devices to secure the iron rest on the upper rear portion of an ironing board 11, or for securing the device to any other suitable supporting structure.

A recess 12 is formed in the bottom of the base 9 and the top of the base is provided with a vertical bore 13 communicating with the recess.

A folding sectional post 14 is slidably mounted in the bore 13 and includes upper and lower sections 15 and 16 pivotally connected to each other as at 17 for vertical swinging movement of the upper section of the post into either a vertical or horizontal position. The lower end of the lower section 16 of the post is provided with a flange 18 and by moving the post downwardly the lower end of the upper section 15 enters the bore 13 to support the upper section of the post in a vertical position while the flange 18 rests on the ironing board 11. By raising the post the upper section 15 thereof is free to swing downwardly into a folded position as shown in Figure 3 of the drawings.

To the upper section 15 of the post is suitably secured a housing 19 which includes a bottom portion 20 and a cover 21 telescoping over the walls of the bottom portion. Journaled in the bottom portion 20 of the housing is a spring wound drum 22 formed at its periphery with gear teeth 23 and engaging a gear 24 of reduced ratio which is secured to a shaft 25 journaled in the upper walls of the bottom portion 20, the shaft also having a reel 26 secured thereto. An electric cord 27 has one end extending through an opening 28 in one edge of the housing 19 for winding on the reel 26. The reel 26 is of insulation material and to one side of the reel is suitably secured a pair of conductor rings 29 connected to the cord as shown at 30. A connector 31 for one end of an extension cord 32 is secured in the housing 19 and includes brushes 33 in contact with the rings 29 as shown in Figure 6 of the drawings.

The outer end of the ironing cord 27 is connected to a conventional electric iron 34 in the usual manner and in the operation of the device with the iron rest 5 secured in position to the ironing board as shown in Figure 1 of the draw-

ings the housing 19 for the cord retriever is raised into a vertical position as shown in Figure 4 and the post 14 moved downwardly in the recess 12 whereby the housing 19 is supported in an upright position and with the post 14 rotatable in the bore 13 so that the housing 19 may swing from side to side to prevent undue wear or strain on the cord 27 while the iron is moved into various positions on the ironing board during the ironing operation.

When the iron is not in use the same is placed in the tray 6 of the iron rest and the spring drum 22 automatically winds the cord 27 on the reel 26 to thus prevent twisting of the cord or interference thereof while using the ironing board.

When the ironing board is not in use the housing 19 and post 14 may be raised upwardly to free the upper section 15 of the post from the bore 13 whereupon the housing and upper section of the post may swing downwardly into a horizontal position as shown in Figure 3 for storing in a substantially compact form.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

In a cord retriever for electrical appliances, a foldable reel supporting post including upper and lower post sections pivoted to each other in end to end relation, a supporting base having a vertical bore countersunk at the underside of the base and in which both sections of the post are vertically slideable for raising and lowering the pivoted end of the upper post section into and out of the bore, said upper section of the post being supported in an upstanding position when its pivoted end is lowered into the bore and said upper section of the post being swingable into a horizontal collapsed position overlying the base when the pivoted end of the upper section of the post is raised out of the bore, and a stop on the lower section of the post and slideable therewith in the counterbore to limit raising withdrawing movement of the lower section of the post from the bore.

ALLAN H. CRAMER.
